UNITED STATES PATENT OFFICE.

LE GRAND PARISH, OF NEW YORK, N. Y.

CIRCULATION AND FEED DEVICE FOR LOCOMOTIVES.

1,303,953.

Specification of Letters Patent. Patented May 20, 1919.

Application filed October 19, 1914. Serial No. 867,299.

To all whom it may concern:

Be it known that I, LE GRAND PARISH, a citizen of the United States, residing at New York, county of New York, and State of New York, have invented certain new and useful Improvements in Circulation and Feed Devices for Locomotives, of which the following is a specification.

This invention relates to circulation and feed devices for locomotives and more particularly to an improved arrangement of circulation tubes in a locomotive fire box whereby water from the injector may be introduced into the boiler through the forward end of one or more of the circulation tubes. One of the chief objects of my invention is the provision of novel means whereby the water, as it is being injected into the boiler, is immediately subjected to the action of the hot gases in the fire box. Another object resides in the provision of an improved arrangement of the circulation and feed water connections whereby the normal flow or circulation through the boiler materially assists in the feed operation, particularly when the injector mechanism is first actuated. My invention also contemplates the provision of a delivery member at the discharge ends of the circulation tubes and communicating with two or more thereof, in combination with a feed water connection at the forward ends of such tubes, whereby when water is being injected into one or more of the tubes, a more rapid flow is induced in the other tubes.

The foregoing, together with such other objects as may hereinafter appear or are incident to my invention, I attain by means of a construction which I have illustrated in preferred form in the accompanying drawings, wherein—

Figure 1 is a longitudinal sectional view showing my improvements applied to a locomotive fire box having a deep throat sheet; Fig. 2 is a cross section through the boiler of Fig. 1; Fig. 3 is a longitudinal sectional view illustrating one form of the application of my improvements to a standard form of locomotive fire box in which the front water leg is comparatively short; Fig. 4 is a section through the boiler of Fig. 3; and Fig. 5 is a sectional detail illustrating a modification of my invention.

Referring to the drawings, it will be seen that the general construction of the fire boxes is of the standard type. The fire

boxes are composed of an inside fire box, comprising a tube sheet 1, side sheets 2, back sheet 3 and crown sheet 4; and an outside box, comprising a throat sheet 1^a, side sheet 2^a, back sheet 3^a and cover sheet 4^a. The water legs are closed by a mud ring 5. It will be noted, however, that in Figs. 1 and 2 the throat sheet 1^a is deeper than in the type shown in Figs. 3 and 4. The tube sheet 1 is carried upwardly to the crown sheet 4 in the usual manner, and the ends of the flues 6 are expanded therein. The fire boxes are provided with stay bolts, but as these form no part of the present invention, they have not been shown.

Attention is now directed to Figs. 1 and 2. In this construction I provide a plurality of rearwardly and upwardly extending circulation tubes, preferably eight in number, arranged in two rows, 8 and 8^a. Although these tubes may be secured to the tube sheet 1 and the back sheet 3 in the customary manner, I prefer to extend the ends of the tubes through both sheets of the water legs in the manner shown. A bead 9 is expanded in each tube at the points of passage through the tube sheet 1 and back sheet 3 and the extremities of the tubes are expanded in the sheets 1^a and 3^a. At the rear or discharge ends of the tubes, I provide four delivery members 10, each one of which is common to two circulation tubes. The discharge ends of the delivery tubes open into the space above the crown sheet, preferably at a point approximately at the normal water line. Communication between the boiler and the forward ends of the circulation tubes is obtained by means of extension members 11 of which I prefer to provide one for each tube to more readily compensate for the expansion of the throat sheet. The rear end of each of these members is fastened to the throat sheet over the end of a circulation tube and the forward end of each member extends into the boiler space at a point removed from the tube sheet and is fastened to the boiler sheet or shell 12. The inlet openings 13 are preferably located at the side and above the boiler shell in order to exclude mud and scale.

The extension members for the lower row of tubes, and for the upper row of tubes are provided with washout plugs 14. The two extension members for the middle tubes of the upper row are connected to the usual feed water injector mechanism (not shown).

by means of feed water pipes 15 whereby feed water may be injected into the tubes through the front ends thereof. These tubes may be cleaned by uncoupling the pipes 15.

5 One of the chief advantages of the foregoing arrangement of circulation tubes and feed water devices is that the water is injected into the forward end of the tubes where it is immediately subjected to the action of the hottest gases in the fire box because such ends of the tubes are nearest to the fire bed. The water must also traverse the whole length of the fire box before it mingles with the contents of the boiler, and 10 it will be apparent that the temperature of the feed water as it thus passes through the tubes is at once raised to a high point before commingling, the advantages of which will be clear to those familiar with the art. In 15 addition the feed water is injected in the line of the normal flow or circulation through the tubes which is of material assistance, particularly in the beginning of the injection operation.

20 25 The coupling of pairs of circulation tubes by common delivery tubes in conjunction with my improved arrangement of feed water device is also advantageous as it will be clear that the increased flow taking place 30 in the upper tubes when water is being injected therein induces, by entrainment, a heavier flow through the lower tubes, thus adding to the efficiency of the fire box.

35 It will also be seen that greater efficiency is obtained because of the fact that the extension members communicate with the boiler at a point removed from the tube sheet 1, adjacent to which steam bubbles or blisters frequently form, owing to its proximity to the source of heat.

40 45 It is further to be noted that the extension members can be readily removed for purposes of inspection or repair, and that the extension of the circulation tubes through both walls of the water legs is peculiarly adapted to permit of repairs at the joints.

50 Turning to the construction shown in Figs. 3 and 4, it will be seen that the arrangement of the circulation tubes and feed water connections is modified for adaptation to a standard fire box in which the throat sheet is not so deep as that shown in Figs. 1 and 2. This adaptation may be accomplished in various ways, but I prefer to bend

the middle tubes of the upper row of circulation tubes downward in a reverse curve adjacent to the tube sheet 1, and extend them through both walls of the forward water leg approximately in line with the tubes of the lower row. A pair of extension members 11 establish communication with the boiler, as previously described. By bending the tubes downwardly and to the side, I am enabled to conveniently apply the extension members and forward feed water device to a standard fire box, and am thereby also enabled to apply the same to all of the circulation tubes, if desired. In the construction shown in these figures, I have provided the members 11 with a check valve 16 70 as a modification; and in Fig. 5 another modification in which the delivery members 10 are omitted, is illustrated.

The brick arch is not shown in Fig. 1, as that construction there shown is such that the bricks may be supported accessibly and removably on any of the tubes, as indicated in my issued Patent No. 1,110,815. In the structure of Figs. 3 and 4, the front bricks 17 are of greater length than the usual brick 80 in order that they may be securely supported on the tubes.

It will be seen that I have illustrated my invention in the drawings in simple form and that the arrangement and construction 85 of the parts may be varied without departing from the spirit of my invention.

I claim:

The combination with a locomotive boiler having a fire-box, water spaces, and a normal circulation tube of substantially uniform flow capacity throughout extending through the fire-box rearwardly and upwardly and connecting water spaces to establish normal circulation of water therebetween, of means for utilizing said tube as a heater of feed water comprising a feed water delivery member communicating with the tube at the forward end thereof without restricting the same, whereby feed water 95 may be injected into said tube.

In testimony whereof I have hereunto signed my name in the presence of the two subscribed witnesses.

LE GRAND PARISH.
